UNITED STATES PATENT OFFICE

137,197

DESIGN FOR A COMBINED EYESHIELD AND RESPIRATOR

Joseph E. Du Bois, Detroit, Mich., assignor, by direct and mesne assignments, of one-fifth to Virginia I. Du Bois, Detroit, Mich., one-fifth to Lauriene T. Holzworth, North Tonawanda, N. Y., one-fifth to Rita C. Sterne, one-fifth to Eileen Silbert, and one-fifth to Florence E. Taylor, all of Buffalo, N. Y.

Application February 20, 1943, Serial No. 109,590

Term of patent 14 years

To all whom it may concern:

Be it known that I, Joseph E. Du Bois, a citizen of the United States, residing at Detroit, county of Wayne, in the State of Michigan, have invented a new, original, and ornamental Design for a Combined EYESHIELD and RESPIRATOR, of which the following is a specification, reference being made to the accompanying drawing, forming part thereof.

Fig. 1 is a front view of a combined eyeshield and respirator showing my new design.

Fig. 2 is a top plan view thereof.

Fig. 3 is an end view thereof.

I claim:

The ornamental design for a combined eyeshield and respirator, as shown.

JOSEPH E. DU BOIS.
